(57) **CLAIM**

The ornamental design for a changing table as shown and described.

DESCRIPTION

FIG. 1 is a front, left, top perspective view of a changing table, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2; and,

FIG. 12 is an enlarged view of detail 12 in FIG. 2.

The broken lines depict portions of the changing table that form no part of the claimed design. The dot dash dot broken lines depict bounds of the enlargements and form no part of the claimed design.

1 Claim, 12 Drawing Sheets
